UNITED STATES PATENT OFFICE.

FRIEDRICH BAUER, OF BROOKLYN, NEW YORK.

PIVOTED PROP.

SPECIFICATION forming part of Letters Patent No. 783,852, dated February 28, 1905.

Application filed December 29, 1904. Serial No. 238,758.

To all whom it may concern:

Be it known that I, FRIEDRICH BAUER, a citizen of the United States, residing at Brooklyn, in the State of New York, have invented new and useful Improvements in Pivoted Props, of which the following is a specification.

This invention has relation to pivoted props especially adapted to be used on the front board of piano-casings; and it consists of the novel construction and arrangement of its parts, as hereinafter shown and described.

The object of the invention is to provide a prop adapted to be attached to the front hinged board of a piano-casing. The said board is provided with a handle, through center of which extends a spring-actuated pin, the inner end of which is adapted to engage a shoulder or offset of the prop for lifting the same on its pivotal point. When the lower edge of the hinged front board of the piano-casing is swung out, the said prop is adapted to fall by gravity in such position that its lower end will come in contact with a fixed portion of the piano-casing and hold the hinged front board out in an incline position. When it is desired to close the hinged board, the pin extending through the handle above referred to is pushed, which elevates the inner or lower end of the prop, so that it may clear the stationary part of the casing, and the hinged front being without support of the prop by action of gravity resumes its normal or closed position. By utilizing this construction of prop the front hinged board of a piano may also be easily swung open to assume a position at right angles to the casing proper, enabling the operator to expose the works and action of the piano to view.

In the accompanying drawings, Figure 1 is a front elevation of the front hinged board of a piano-casing, showing the prop attached thereto. Fig. 2 is a transverse sectional view of the front board of a piano-casing, showing the prop in elevated position. Fig. 3 is a transverse sectional view of the front board of a piano-casing, showing the prop down and supporting the front board at an incline. Fig. 4 is a top plan view of the prop proper. Fig. 5 is a transverse sectional view through the front board of the piano-desk, showing the handle

and pin located therein and the inner portion of the prop. Fig. 6 is a side elevation of the prop.

The prop 1 may be made of metal or any other suitable material and is preferably curved along its longitudinal axis. The said prop at its inner end is provided with a shoulder or offset 2 and is adapted to be pivoted at the point 3 to the fittings 4, which in turn are secured to the rear face of the hinged front board 5 of the piano-casing. The handle 6 is attached to the front board 5, and the pin extends through the said handle 6. The coil-spring 8 is interposed between an enlarged portion of the pin 7 and the inner side of the handle 6. The tension of the said spring 8 keeps the pin in its normal position as far away as possible from contact with the shoulder 2 of the prop 1. The inner end of said pin 7 is provided with an enlarged head 9, which is adapted to engage the shoulder 2 of the said prop.

The operation of the device is as follows: When it is desired to open the front board 5 at an angle, as shown in Fig. 3 of the drawings, the lower edge of the said front board is swung out and the end of the prop 1 falls by gravity, engaging the side of the stationary portion 10 of the piano-casing. Thus the front board is maintained in the said inclined position. When it is desired to close the front board back into position, as shown in Fig. 2, the handle 6 is grasped and the pin 7 is pressed back against the tension of the spring 8. The enlarged head 9 of said pin engages the shoulder 2 of the prop 1 and lifts the lower end of the said prop up over the edge of the portion 10 of the piano-casing. By reason of the curvature of the longitudinal axis of the prop 1 the said prop resting upon the edge of the portion 10 is swung up into the position as shown in Fig. 2 as the front board is swung back.

The spring 8 is not absolutely essential to the operation of the device, for the reason that the weight of the prop 1 is ordinarily sufficient to keep the pin 7 in the outer position with relation to the handle 6 without the use of said spring.

Having described my invention, what I

claim as new, and desire to secure by Letters Patent, is—

1. A device of the character as described consisting of a hinged board, a prop pivoted at 5 one end thereto and adapted to engage at its other end a stationary point, a reciprocating pin located in the said board adjacent the pivoted end of the prop and adapted to engage said prop and move same on its pivotal point.
- 10 2. A device of the character as described consisting of a hinged board, a prop pivotally attached thereto and adapted to engage at one end a stationary point, a handle attached to the board adjacent the pivoted point of said 15 prop, a pin passing through said handle and adapted to engage the prop and move the same on its pivotal point.
- 20 3. A device of the character as described, consisting of a hinged board, a prop pivotally attached thereto and adapted to engage at one end a stationary point, a handle attached to said board adjacent the pivotal point of the prop, a spring-actuated pin passing through 25 said handle and adapted to engage the prop to move the same on its pivotal point.
- 25 4. A device of the character as described

consisting of a hinged board, a prop pivotally attached thereto, being curved along its longitudinal axis and adapted to engage at one end a stationary point, a pin carried by the 30 hinged board and adapted to engage the prop to move the same on its pivotal point.

5. A device of the character as described consisting of a hinged board, a prop pivotally attached thereto and having a shoulder, a pin 35 carried by said board and adapted to engage a shoulder of the prop to move same on its pivotal point.

6. A device of the character as described consisting of a hinged board, a prop pivotally 40 attached thereto and being curved along its longitudinal axis and having a shoulder, a pin carried by said hinged board and adapted to engage the shoulder of the prop to move the same on its pivotal point. 45

In testimony whereof I affix my signature in presence of two subscribing witnesses.

FRIEDRICH BAUER.
